Hazard Principle of Bedlam Connecticut
S. M. D. - 1853

The Committee found to my great Satisfaction and making part of the
above continuing order of plan in the month of the said Hazard to resolve himself
of his improvement in the construction of his Whited Carriages by which
the impulsive effects of sudden obstruction, or the sudden arrest of
the advancing and descending of body facilitated.

To all whom it may concern. - I, S. M. D. of the Village of New Haven in the County of New Haven and State of Connecticut, have
invented a new and useful mode of applying spiral coiled springs
to the axles and other whited carriages by which the bodies of such carri-
ges are allowed to advance forward when the wheels are suddenly checked
by any obstruction or halting and the impulsive and injurious ef-
fect resulting from the immediate stoppage of the momentum of such
carriages is greatly diminished, and the position of the load is
so changed in ascending as in descending hills as to be more favorable
to the draft of the horse. And I do hereby declare that the following is a
full and exact description of my said invention. The spring which I use
to prevent the direct meeting of the momentum of the body of the carriage
is usually of the spiral kind which I consider as best adapted to the
purpose. This spring is contained within a clevis staple or other appen-
dage as shown in No. 1. in the accompanying drawing which represents
the said spring and its staple &c. a. a. is a clevis or staple secured to
the draw bar b. containing within it the spiral spring c. c. The ends
of this spiral spring bear against circular caps with projecting pins to
secure them through holes in these caps and also in the draw bar
and in the head of the clevis plates that slide on the draw bar at a set
distance, the spring may be from 3 to 9 inches in length and 3 inches
in diameter and a thickness of 2 or 3 inches in length will then have a
good proportion to the spring. It may be made round or otherwise
as the spring and its staples, and the other parts of the carriages will
allow.

The part *c* embraces the whiffetree, and is secured to it by a bolt. Below the *whiffetree* is a through the center of the opening, two loops of leather are made, outside of each cap, and having heads on their ends, pass thru the slot and resting on the spring thru the medium of the caps, and the motion of the vehicle in either direction. The *whiffetree* No. 3, has points at the ends, off to receive metallic or other rods, 3.3. which may be 2 feet or more long, and must be of sufficient strength to hold back as well as draw the vehicle by the forward ends. These rods are bent at the forward ends, 3.3. as to hold the bridle and to hold the teams. The rods may pass either above or under the thills and these loops of leather fastened to the thills, about 4 or 5 inches from the forward ends of the rods. No. 4, is a rod of iron or other material extending from the forked end *c*, of the stirle to the underside of the body. Instead of connecting the ends of this bar to the bony of the stirle, & to the whiffetree by iron eyes, I usually employ a loop of leather, strengthened by doubling it, the tail of the whiffetree passing thru one of these loops. & another bolt is used to attach the other end to the body. The load is drawn by means of this rod. Below the stirle body of the vehicle I place two pieces of wood or metal *b*. No. 5, which rest upon the through braces, in a gig wheel or have in use. These are three feet 2 inches in length and in form resemble a cradle spring inverted. They are connected together by a cross bar fastened at its inner ends, are wings of metal, *jj*, about 9 inches long extending in from the stirle body and firmly fastened to them, eyes, or staples, *kk*, secured to the underside of the carriage body enable it to slide backward and forward upon the wings, *jj*, which they embrace. There are many other methods in which this sliding part may be constructed, but the foregoing may do as an exemplification of its mode or principle of action. From the sliding motion of the carriage, the play of the top shank may not always be sufficient to render the carriage perfectly free to obviate which difficulty, it makes the top shank after the thills longer than usual; but they need not be longitudinal in a degree equal to the required play, as the shank itself, will reduce the intended pressure to a considerable extent. By this arrangement however, the horse and rider will not only be relieved from the effects of sudden startings on the road but the bearing of the thills, the position of the body & load of the vehicle, when ascending or descending hills will be so changed as to be favorable to the draft of the horse. *jjjj* of claim as my invention is the manner of placing the coil spring or springs to combine with the sliding motion of the body of a two wheel

arrive as to produce the effects described, whether the separate parts be considered as -
acting in the aggregate before all, or in any other operating upon the same principles -
or in producing the same effects.
